SAFETY DEVICE FOR WRINGERS

Ernest C. Hill, Medford, Mass.

Application August 15, 1935, Serial No. 36,289

5 Claims. (CL. 192—138)

This invention relates to a safety device for a clothes wringer.

One object of my invention is to provide a safety device for an electrically or power driven wringer which will automatically shut off the motor when the fingers or hands, or any other part of the operator, are in any position where they are likely to be caught in the wringer. It is a preventive of accidents by eliminating their cause before they can happen.

Another object is to make my device simple in construction and operation so that it will add but little to the selling price of a wringer. Still another object is to so construct my device that it can be made as an accessory and attached to or used in conjunction with wringers already in use at small expense.

The foregoing and other objects which will appear as the nature of the invention is better understood, may be accomplished by a construction, combination and operative arrangement of parts such as is disclosed by the drawing. The nature of the invention is such as to render it susceptible to various changes and modifications, and, therefore, I am not to be limited to the construction disclosed by the drawing; but am entitled to all such changes therefrom as fall within the scope of my claims.

In the drawing:

Figure 1 is a perspective view of an electrically driven wringer with my safety device attached thereto.

Figure 2 is an end elevation, sectional view taken on the line 2—2 of Figure 1.

Figure 3 is a front elevation view, partly in section, and broken away, showing a portion of my safety device attached to a wringer with the switch partly broken away and in open position.

Figure 4 is a section taken on the line 4—4 of Figure 3, illustrating part of the switch, and showing it in closed position.

As illustrated, my device is operable in combination with an ordinary type of electrically or power driven wringer 12, and is shown attached thereto. Said wringer 12 has a top 14, and two sides 13 which are at each end of the wringer rolls 15. I have designated the space left between the wringer rolls as 16. It has a supporting pan 17 and the usual gear and driving means 18.

My device has a switch box 22 supported by a bracket 23 which is shown fastened to a side 13 of the wringer by screws 24. Said switch box 22 has a top plate 25 having a slot 26 therein

through which an extension bar 27 passes, which bar is attached at one end to a resetting knob 28 for the switch, by a bolt 29. Said extension bar 27 has a longitudinal slot 30 through which a horizontal finger 31 extends which permits said bar 27 to move vertically while said finger 31 remains in said slot 30. A movable bracket 32 is movably mounted in a frame 33. Said extension bar 27 is fastened to said movable bracket 32 by means of the bracket offset member 34 fitting into a hole in said bar 27, so that they will move together upon actuation. Extending from said movable bracket 32 is a movable switch contact member 35, while above it is a stationary switch contact member 36, being the usual contact members in well known switches, and when they are in contact with each other the switch is closed and the current is on, whereby the wringer is operated, and while they are out of contact, as illustrated in Figure 3 of the drawing, the switch is open, the current is off and the wringer ceases to operate. A long switch button or finger 37 is fastened to the said movable bracket 32, the position of which finger determines whether or not the switch is open or closed, as later described. A coil spring 38 fastened to said offset member 34 at one end and to said horizontal finger 31 at the other end is under tension when said switch finger 37 is depressed and the switch closed.

My safety device has an oscillating lever 40 shown at the left side of the wringer 12, movement of which opens the switch and shuts off the circuit, there being a somewhat similar lever 43 at the other side, later described. Said lever 40 has an extension arm 41 having two holes 42 therein spaced apart, the portion of said arm between said holes I term the bridge portion 43. When said switch finger 37 extends through either hole 42 the switch is open and the circuit broken; but when the button is underneath said arm 41 and abutting against said bridge portion 43, as illustrated in Figure 4 of the drawing, the switch is closed, said contact members 35 and 36 being together. Said lever 40 is pivotally mounted on a rod 45 which is fastened to a side 13 of the said wringer 12, so that movement of said lever 40 forward or backward moves said extension arm 41, thereby presenting one or the other of said holes 42 directly over said switch finger 37, which, being under spring pressure, immediately passes upwardly into a hole 42, which results in said contact member 35 moving downwardly away from said contact member 36 thus opening the switch and

cutting off the supply of electricity which operates the wringer. Connected to said levers 40 and 63 are guard means 47 at the front of and also at the rear of the wringer, pressure against which results in actuating said extension arm 41 to open the switch as described. Should a person's fingers, hand or other part be moved to such a position that there is danger of being caught between the said wringer rolls 15 or 10 actually caught therein, they will contact with and exert pressure on said guard means 47 to thereby oscillate said levers 40 and 63 and move said arm 41 to thereby shut off the supply of electricity. This pressure against the guard means 47 may be in a forward or backward direction, and in either event said switch finger 37 will have a hole 42 presented opposite and above it into which hole it will pass to thereby open the circuit.

20 Said guard means 47 has an upper rod 48 both ends of which are connected to said levers 40 and 63 by sleeves 49 in which the ends of said rod 48 engage, there being stub rods 50 engaging said sleeves 49 at their outside ends, said stub rods 25 being fastened to said levers 40 and 63 by nuts 51. While I have shown this particular construction of rods and sleeves just described it will be understood that it may be varied, and, if desired, a single rod may be used which extends from the said lever 40 to the other lever 63 and directly connected thereto.

Screws 53 loosely extend through said sleeves 49, not being screw threadedly engaged therewith, and screw into combined nuts and elbows 35 54, with which the ends of a lower rod 55 engage, so that there are rods opposite each wringer roll 15, one above the other. Thumb nuts 57 screw on said screws 53 above said sleeves 49 and locking nuts 58 also screw on said screw 53 below said sleeves 49, so that if it is desired to move said rods 48 and 55 nearer or farther away from each other said nuts 57 and 58 may be moved accordingly, thus providing an adjustment feature to my guard means which is desirable on account 45 of the difference in size of the hands and fingers of persons who may use the wringer.

Loosely mounted and rotatable on said upper rod 48 is a roller 60 which will rotate on said rod 48 as the clothes to be wrung come in contact with it. Of course, any substantial pressure against it will move said guard means 47 and oscillate said lever 40 and open the switch; but it will merely rotate as a result of the light pressure of the articles to be wrung passing over it. On the said lower rod 55 is a roller 61 similar to the said roller 60 and for the same purpose. These rollers 60 and 61 may be spaced from the wringer rolls about $\frac{1}{4}$ of an inch, which distance has been found effective. Extending as they do 60 directly in front of each wringer roll 15, when the fingers or hands are dangerously close to said wringer rolls they will press against one of said rollers 60 and 61 and thereby shut off the current as previously described. This is true whether they are pushed or pulled as movement of the lever arm 41 to either side presents a hole 42 opposite said finger 37 into which it will pass.

At the right side of the wringer and pivotally mounted thereto is an oscillating lever 63 which 70 is connected to the said lever 40 as previously described, so that substantial pressure on any part of the said guard means 47 will result in opening the switch. This lever 63 is of somewhat different shape than the lever 40, having ears 64 at 75 the front and back, each ear having a hole 65

therein, in each of which one end of a coil spring 66 is fastened, the other end being fastened to a small bracket 67 which is held by a bolt 68 to the wringer. There is a said coil spring 66 at the front and one at the back of the wringer, and these opposing springs serve to keep said levers 40 and 63 in equilibrium in a predetermined position, in which the position of the switch finger 37 under and against the said bridge portion 43 is normally maintained, the switch, as previously 10 explained, then being in closed position.

When the switch is opened and the operation of the wringer thereby stopped, it can instantly be started again by merely pressing the said resetting knob 28, which moves said switch finger 15 37 out of a said hole 42 whereupon the springs 66 restore the levers 40 and 63 to their normal position and the switch finger 37 automatically moves to its normal position against the under side of the bridge portion 43, and the switch is again in 20 closed position.

Inasmuch as electrically driven wringers are commonly made reversible I provide said guard means 47 at the front and rear of said wringer.

What I claim is:

1. A safety device comprising movable lever means embodying an arm extending outwardly and having a plurality of holes therein, spring means connected to and adapted to hold said lever means in a predetermined position, electrical switching instrumentalities embodying a finger adapted upon actuation to open and close said instrumentalities and adapted to enter said holes, and a spring operatively connected to said finger, said finger bearing against the under side 35 of said arm between said holes under tension of said spring when said lever means is in said predetermined position, and guard means connected to said lever means movement of which guard means is adapted to move said arm and thereby 40 present one of said holes opposite said finger whereby said finger may enter said hole.

2. A safety device comprising movable lever means embodying an arm extending outwardly and having a plurality of holes therein, electrical 45 switching instrumentalities embodying a finger adapted to enter said holes, movement of which finger opens and closes said switching instrumentalities, a bar, means connecting said finger and bar together whereby they may be actuated together, a spring operatively connected to said bar and finger, said bar, finger and spring being so positioned that movement of said bar downwardly depresses said finger and tensions said spring, and guard means connected to said lever 50 means, movement of which guard means is adapted to move said arm.

3. In combination, a motor driven wringer and a safety device, said safety device comprising a movable lever pivotally fastened to each side of said wringer, one said lever embodying an arm extending outwardly and having a hole therein to receive a finger, guard means extending between and connected to said levers, spring means fastened to one said lever and to said wringer, electrical switching instrumentalities embodying a finger actuation of which opens and closes said switching instrumentalities, said spring means normally holding said levers in such position that said finger abuts against said arm; said guard 70 means being adapted to be moved whereby said arm is moved and said hole is presented opposite said finger.

4. A safety device comprising two movable lever members spaced apart, electrical switching 75

instrumentalities connected to and adapted to be actuated by the movement of one of said lever members, rod means extending between said lever members embodying two rods spaced apart one above the other, one of said rods being fastened to said lever members, means connecting said rods together, a roller on each said rod adapted to rotate thereon, two springs fastened to one of said lever members at opposite sides adapted to hold said rod means in a predetermined position, said switching instrumentalities and said lever member connected thereto being so positioned relative to each other that when said rod means are in a predetermined position said switching instrumentalities are closed.

5. In combination, a motor driven wringer having two wringer rolls, and a safety device, said safety device comprising two levers movably attached to said wringer one at each side thereof and connected together, one of said levers embodying an arm extending outwardly therefrom and having a plurality of holes therein spaced apart, electrical switching instrumentalities

adapted to be actuated by the movement of said levers embodying a button at the outside of said instrumentalities, a finger adapted to extend into said holes in said arm, means operatively connecting said button and finger together whereby actuation of said button actuates said finger, said finger being adapted to abut against the under side of said arm between said holes when said instrumentalities are in closed position, guard means connected to said levers embodying rod 10 means, said rod means embodying two rods one above the other and spaced from and directly opposite said wringer rolls, means connecting said rods, and spring members fastened to one of said levers and to said wringer, said spring members 15 being adapted to hold said guard means in a predetermined position whereby said finger normally abuts against the under side of said arm, said guard means being adapted to be moved to such a position that one of the said holes in said arm 20 is presented opposite and above said finger whereby said finger may enter it.
